REFRIGERATION

Robert Lay Hallock, Larchmont, N. Y.

Application May 16, 1934, Serial No. 725,845

7 Claims. (Cl. 62—108.5)

My invention relates to refrigeration and more particularly to mechanism for removing an ice tray from an evaporator to which it may be frozen.

5 The object of my invention is to provide an arrangement which: is independent of the ice tray itself; acts both to lift the ice tray from the shelf to which it may be frozen and move the ice tray forwardly; is not affected by thickness of ice film on the shelf; provides a large moving force with application of little initiating force; is sturdy and neat in appearance; is easy to keep clean; and which does not bind.

10 My invention will be understood from the following description of a preferred embodiment shown on the accompanying drawing, which drawing forms a part of this specification, and of which:

15 Fig. 1 is a plan view of an ice tray shown in an evaporator, the apparatus having the invention embodied therein, the evaporator being shown in horizontal cross-sectional view;

Fig. 2 is a side view, partly in section, taken on the line 2—2 of Fig. 1;

20 Fig. 3 is a vertical sectional view taken on the line 3—3 of Fig. 1;

Fig. 4 is a front view; and

Fig. 5 is a transverse vertical sectional view taken on the line 5—5 of Fig. 2.

25 The evaporator comprises shelves 10 on which ice trays are adapted to rest, and side walls 11. The evaporator is cooled to below water freezing temperature by means such as a cooling coil embedded in or in good thermal relation with walls 11. Between the side walls and two shelves 10 is formed a compartment 12 for reception of an ice tray 13. The ice tray includes a body portion of rectangular dish shape adapted to receive water and having a bottom wall 14 adapted 30 to rest on the shelf 10. The body portion is preferably made of bendable metal such as thin aluminum sheet. At the front of the tray body is a flange 15 to which is fastened a tray front 16 bent to form a drawer type handle 17 into which the fingers of the operator may be inserted upwardly for drawing the tray out of the compartment 12. A web or flange 18 is formed at the forward, left-hand corner of the tray. This web 18 may, and preferably does, meet the flange 15 for purposes of rigidity and a like web 35 may be provided on the opposite side of the tray. The lower part of web 18 may be bent inwardly as shown at 19 (Fig. 5) and the bottom of this web provides an inclined surface 20 which 40 extends forwardly and downwardly.

The front of the evaporator is provided with a cover plate 21 having an aperture 22 through which the ice tray is inserted and a second aperture 23 through which extends a lever or finger piece 24. Cover plate 21 is suitably fixedly secured to the evaporator structure formed by the side walls 11 and the shelves 10.

45 A boss 25 is provided on the left-hand side wall, as shown. This boss and its associated mechanism and the inclined surface 20 may be provided on the opposite side of the ice tray if desired, but preferably only one such structure is provided. The boss 25 is provided with a horizontal bore or aperture 26 in which is journalled a shaft 27 integral with the lever or finger piece 24. On the inside of the wall 11 a cam member 28 is secured to member 27 as by a pin 29. The shape of the cam member is shown in Fig. 3. With the lever 24 in down position the cam 28 does not touch the tray. The cam member 28 is positioned just under the surface 20 and is of such form and so positioned, about midway of the height of the tray, that on raising the finger piece 24, the cam member 28 contacts the inclined surface 20. This 50 imparts a force against the surface 20 and due to the incline of the surface 20 this force has both a lifting component and a forward pushing component. By lifting on the finger piece 24 the cam 28 bears upwardly against the web 18 and thus prys the tray from the shelf beginning at one corner. The shelf being made of flexible material and being twistable diagonally, the tray can be progressively peeled from the shelf due to the lifting of the finger piece 24 and the action 55 of cam 28. The plate 16 acts as a stop to prevent the tray from being lifted by contact with the cam on inserting the tray into the compartment 12. The arrangement is such that in case the lever 24 should be stuck in up position, on reinserting the tray into the compartment 12 the surface 20 will contact the cam and return the lever to down position. Normally the lever will fall to down position when it is released. The cam 28 on being turned by upward lifting lever 45 24 first peels the tray from the shelf and then moves the tray outwardly. The tray may be pushed entirely within the compartment 12 and the outward movement due to operation of cam 28 may cause the tray handle to be exposed so 60 that it can be grasped.

65 It will be seen that the releasing mechanism is entirely above the shelf and that it is of such construction that it cannot become ice-bound. It will be understood that there will be a series 65

of levers 24 one above the other, one for each tray. The lever 24 may be lifted by placing the thumb on a higher level and using a finger to lift the particular lever for freeing the desired 5 ice tray.

I have shown only a preferred form of the invention but it will be understood that various modifications may be made within the spirit and scope of the invention.

10. What I claim is:

1. The combination with an evaporator having a shelf and a side wall, of turnable means mounted on said side wall above said shelf for releasing an ice tray supported by said evaporator,

15. said means being constructed and arranged to exert force against such tray above said shelf and being itself entirely independent of said shelf.

2. In refrigerating apparatus, an evaporator, a diagonally twistable tray adapted to be supported by said evaporator, and means mounted 20 on the evaporator and constructed and arranged to exert force against said tray at a different level than that at which the tray is supported to pry said tray from the evaporator by diagonal twisting beginning at one corner of the tray.

25. 3. In refrigerating apparatus, an evaporator, a tray adapted to be supported by said evaporator having a part providing a forwardly and downwardly extending surface, a cam member mounted on said evaporator adapted to contact said

surface, and a forwardly extending lever for turning said cam member.

4. The combination with an evaporator having a shelf and a side wall, and an ice tray adapted to be supported by said evaporator, of a turnable member mounted on said side wall and engageable with a portion of said ice tray above said shelf to release said tray from said shelf. 5

5. In refrigerating apparatus, an evaporator having a shelf and a side wall, an ice tray adapted to be supported on said shelf, said ice tray having a part providing an inclined plane, and a cam adapted to act against said inclined plane and mounted on said side wall.

6. In refrigerating apparatus, an evaporator 15 member having a shelf and a side wall, a front plate for said evaporator member having a first aperture for insertion of an ice tray and a second aperture to one side of said first aperture, and a tray moving lever mounted on said side wall 20 above said shelf and having an arm projecting through said second aperture and constructed and arranged to contact the tray above said shelf to release the tray from the shelf.

7. The combination with an evaporator shelf 25 and a tray supported thereby and having a surface above said shelf, of means mounted above said shelf for imparting a force to said surface having lifting and forwardly pushing components. 30

ROBERT LAY HALLOCK.
